CHARLES F. STODDARD, OF BOSTON, MASSACHUSETTS, ASSIGNOR TO AMERICAN PNEUMATIC SERVICE COMPANY, OF DOVER, DELAWARE, A CORPORATION OF DELAWARE.

PNEUMATIC-DESPATCH APPARATUS.

SPECIFICATION forming part of Letters Patent No. 758,569, dated April 26, 1904.

Application filed May 7, 1903. Serial No. 155,990. (No model.)

To all whom it may concern:

Be it known that I, CHARLES F. STODDARD, of Boston, in the county of Suffolk and State of Massachusetts, have invented certain new and useful Improvements in Pneumatic-Despatch Apparatus, of which the following is a specification.

My invention relates to new and useful improvements in pneumatic-despatch apparatus; and its object is to produce a novel and efficient closed receiver for receiving carriers from the main tube-line or transmission-tube.

My invention consists of certain novel features hereinafter described, and particularly pointed out in the claims.

The accompanying drawing represents a longitudinal section through my improved closed receiver.

From the transmission-tube A, through which the carrier travels, the air is carried off through the pipe B through the slotted casing C, having a number of slots C'. Beyond the slotted casing C is the compression-chamber D, communicating with the valve-chamber D', and between the valve chamber D' and the valve-chamber D³ is a connecting-pipe D², and beyond the valve-casing D³ is a table D⁴ to receive the carriers and a buffer E for cushioning the carriers passing onto the table. The table is supported by the legs F' F' and the receiver by the legs F F. Within the valve-casings D' and D³ are the valves G' and G, respectively, provided with counterweights G³ and G². These valves G and G' swing on the shafts G⁴ and G⁵, suitably supported in the sides of the valve-casings D³ and D⁴, and on the outside of the valve-casings D³ and D' are located the counterweights G² G³ on the ends of the shafts G⁴ G⁵. The valve-casing D³ is in open communication with the atmosphere through the port H. The rod J, extending along the outside of the valve-casing D³, is connected to the rod J² by means of the rocker J', and the rod J² is pivotally connected to the rocker-latch J³.

L L' L³ L⁴ are pins connecting the rods J and J² J', the rod J², and the rocker-latch J³.

The relief-port P, connecting the chambers

D and D² through the port P', is controlled by the valve P² on the rod P⁴, which is operated by the diaphragm P³, held on the rod P⁴ between the plates P⁵ P⁶ and normally held closed by the spring P⁷.

Q is a shoulder on the rod P⁴, and Q² is a pawl on the rocker-latch J³, which engages the shoulder Q, as hereinafter described. Through the pipe R pressure is provided to the rear side of the diaphragm P³ to balance it when the machine is in its normal position. The valves G and G' are constructed so that their areas above the shafts G⁴ G⁵ are larger than the areas of the portions below the shafts. This arrangement makes the pressure on the valves G G' greater above the shafts than below and tends to keep the valves tightly closed. The counterweights G² G³ bring the valves G G' into a closed position after they have been opened. The carrier coming in from the transmission-tube A passes through the slotted casing C into the compression-chamber D and is slackened in speed by compressing the air in front of it. This compressed air in front of the carrier communicates with the front side of the diaphragm P³ through the port P, and as this pressure is greater than the pressure back of the carrier, which is communicated to the back side of the diaphragm P³ through the pipe R, it throws the diaphragm to the opposite side of the chamber from that shown in the figure and opens the valve P². The diaphragm is held in its open position by the pawls Q² and the rocker-latch J³, dropping in front of the shoulder Q. This relieves the pressure in front of the carrier by allowing it to pass into the atmosphere through the port P, port P', chamber D², and port H in the valve-casing D³. The carrier continues its travel under diminished speed controlled by the size of the port H until it strikes the valve G', which it swings open, and passes under the same into the chamber D², the valve G' closing by the counterweight G³ immediately after the carrier has passed out from under it. The carrier moving ahead still under reduced speed strikes the valve G, and opening the same it then passes onto the ta-

- ble D⁴. As the valve G reaches its full open position the counterweight G² strikes the rod J, which communicates the motion through the rocker J' to the rod J², which in turn pulls the rocker-latch J³ against the tension of the spring S, and this operation pulls the pawl Q² away from the shoulder Q, releasing the rod P⁴, when the spring P⁷ pushes the diaphragm P⁸ back into its normal position, thereby closing the valve P⁹. After the carrier has passed out under the valve G onto the table D⁴ the counterweight G² immediately closes the valve G, leaving the closed receiver in position for another operation.
- 15 Having thus described the nature of my invention and set forth a construction embodying the same, what I claim as new, and desire to secure by Letters Patent of the United States, is—
- 20 1. In an apparatus of the character described, a terminal, and valves located in said terminal and adapted to be opened for the passage of the carrier by the carrier and having their greater area located out of the line of travel of the carrier and in the same plane as the smaller area.
- 25 2. In an apparatus of the character described, a terminal, valves located in said terminal and adapted to be opened for the passage of the carrier by the carrier and having their greater area located out of the line of travel of the carrier and in the same plane as the smaller area, and means for closing said valves after the passage of the carrier.
- 30 3. In an apparatus of the character described, a terminal, and unbalanced valves located in said terminal and adapted to be opened for the passage of the carrier by the carrier and having their greater area located out of the line of travel of the carrier and in the same plane as the smaller area.
- 35 4. In an apparatus of the character described, a terminal, unbalanced valves in said terminal and adapted to be opened for the passage of the carrier by the carrier and having

their greater area located out of the line of travel of the carrier and in the same plane as the smaller area, and means for closing said valves after the passage of the carrier.

5. In an apparatus of the character described, a terminal, a valve located in said terminal and adapted to be opened for the passage of the carrier by the carrier, means for closing said valve after the passage of the carrier, a passage around said valve for the compressed air ahead of the carrier, a relief-valve normally closing said passage and adapted to be opened by the air compressed by the carrier, means for holding said relief-valve open, and mechanism for releasing said relief-valve to allow the same to close on the passage of the carrier from the terminal.

6. In an apparatus of the character described, a terminal, a valve located in said terminal and adapted to be opened for the passage of the carrier by the carrier, a passage around said valve for the compressed air ahead of the carrier, a relief-valve normally closing said passage and adapted to be opened by the air compressed ahead of the carrier, yielding means for holding said relief-valve closed, means for holding said relief-valve open, a second valve in the terminal located in the line of travel of the carrier and adapted to be opened for the passage of the carrier by the carrier, means for closing said second valve after the passage of the carrier, and mechanism operated by the movement of said second valve for releasing said relief-valve to allow the same to close on the passage of the carrier from the terminal.

In testimony whereof I have signed my name to this specification, in the presence of two subscribing witnesses, this 18th day of April, A. D. 1903.

CHARLES F. STODDARD.
